INVENTOR

LENIS H. WRIGHT

Wright & Co.

ATTORNEY

UNITED STATES PATENT OFFICE.

LENIS HOWE WRIGHT, OF LOS ANGELES, CALIFORNIA.

AEROSTATIC SIGN.

Application filed February 9, 1927. Serial No. 186,986.

My invention relates to aerostatic signs, and a purpose of my invention is the provision of a sign in which the letters or other characters thereof constituting the sign are each individual balloons so that the letters themselves provide the means for sustaining the sign as a whole in the air.

It is also a purpose of my invention to provide a sign of the above described character in which means is provided for holding the sign characters in reading relation to each other and yet allowing bodily movement of the sign as a whole at a fixed elevation so that the sign characters and the assembling means will be held against entanglement and possible injury.

I will describe only two forms of aerostatic sign embodying my invention, and will then point out the novel features thereof in claims.

In the accompanying drawings,

Figure 1 is a view showing in perspective one form of aerostatic sign embodying my invention;

Figure 2 is a view similar to Figure 1 showing another form of aerostatic sign embodying my invention;

Figure 3 is an enlarged detail view showing in vertical section one of the sign characters embodied in either of the signs shown in Figures 1 and 2.

The form of sign shown in Figure 1 comprises a plurality of characters, each of which as illustrated to advantage in Figure 3, comprises a fluid-tight bag 15 formed of rubber, silk or other suitable material and which is adapted to be inflated with a suitable gas for rendering the bag self-sustaining in the air. The construction of the bag is such that when inflated its widest portion is disposed uppermost in order that the character which it represents may be positioned in the air to be readable from the ground. To aid in confining the bag against destruction when inflated, a netting 16 is arranged in embracing relation to the bag.

As shown in Figure 1, the sign is made up of a plurality of characters such as described in connection with Figure 3, and these characters are arranged one above the other and held in this superposed position by the provision of a suitable frame constructed of cables. The characters in the present instance constitute letters arranged so as to be readable from the ground in the formation of the word "may". The frame

comprises a length of cable including vertical portions 17 and a horizontal portion 18, the vertical portions being connected at intervals by transverse cables 19 and at their lower ends by a cable 20. The horizontal cable portion 18 and the transverse cables 19 and 20 are extended through suitable sleeves 21 provided on the bags constituting the letters, the arrangement of the cables and sleeves being such as to maintain each letter in upright position and to thereby be readily readable from the ground.

Connected to the cable 20 are a plurality of depending cables 22 converging and connected to a swivel 23, the latter, in turn, being connected to a master cable 24 which constitutes means for rendering the sign as a whole captive, it being understood that the cable is anchored to the ground.

By the provision of the cable 24, the sign can be sustained at any desired height within the air, the swivel connection 23 permitting rotative movement of the sign as a whole on the cable 24 so that the sign characters and the supporting frame are free to rotate under the action of the wind. In this manner, the possibility is eliminated of the cables constituting the frame becoming entangled with a possible injury to the bags forming the sign characters.

Referring now to Figure 2, I have herein shown another form of aerostatic sign which is substantially identical with that shown in Figure 1, with the exception that the sign characters are arranged one beside the other so as to be readable horizontally. The supporting frame for the characters is such as to maintain the latter in definite relation to each other in order that they may be at all times readable from the ground.

It is important to note that the shape of the sign characters is such as to provide convergent sides, the inclination of which is such as to facilitate the reading of each character from the ground.

Although I have herein shown and described only two forms of aerostatic signs embodying my invention, it is to be understood that various changes and modifications may be made therein without departing from the spirit of the invention and the spirit and scope of the appended claims.

I claim as my invention:

1. An aerostatic sign comprising sign characters each consisting of an individual balloon, sleeves provided on the upper and

lower portions of the balloons, a frame for supporting the characters in spaced reading relation comprising cables including portions threaded through the sleeves and other portions connecting the first portions and converging downwardly to a common point, and a master cable connecting the converging portions for rendering the sign captive, each of said balloons being wider at the top than at the bottom so as to have its greater lifting capacity at the top and thereby maintain the characters in upright position.

2. An aerostatic sign comprising sign characters each consisting of an individual balloon, sleeves provided on the upper and lower portions of the balloons, a frame for supporting the characters in spaced reading relation comprising cables including portions threaded through the sleeves and other

portions connecting the first portions and converging downwardly to a common point, and a master cable connecting the converging portions for rendering the sign captive.

3. An aerostatic sign comprising sign characters, each constituting an individual balloon, each of the balloons being so shaped as to have greater internal area at the top than at the bottom so that when inflated, a greater lifting force will be exerted at the top than at the bottom of the balloon to thereby tend to maintain the balloon in an upright position, means for maintaining the characters in definite and reading relation, and means connected to the first means for rendering the characters captive to maintain the latter at a fixed elevation in the air for reading of the characters from the ground.

LENIS HOWE WRIGHT.
